UNITED STATES PATENT OFFICE.

SAMUEL BUCHSBAUM, OF CHICAGO, ILLINOIS.

MULTIPLE-GRIP BELT BUCKLE.

Application filed March 23, 1922. Serial No. 546,115.

My invention relates to belt buckles and more particularly to a belt buckle having a gripping member made up of a plurality of gripping units.

5 It is a purpose of the invention to provide a belt buckle which will firmly grip the belt at all portions thereof transversely of the same, and which will conform to any irregularity in the thickness of the belt or any 10 variation in the distance between the pivot of the gripping member and the front plate of the buckle.

It is a further purpose of the invention to provide a belt buckle comprising a front 15 plate and a gripping member adapted to grip a belt end between said member and front plate, which gripping member comprises a plurality of gripping units independently pivotally mounted so that the 20 gripping units may be tilted at varying angles relative to the front plate, so that the belt will be gripped firmly by all of said gripping members no matter what the contour of the belt or front plate may be.

25 It is still a further purpose of the invention to provide a belt buckle with a gripping member of the above mentioned character which comprises gripping units that are relatively thin so that the same may be stamped out at comparatively a small cost, said gripping units being identical in shape and preferably being each provided with a portion which is adapted to be engaged by a member carrying means for holding the 30 other end of the belt for moving the gripping member into position to grip the belt and with means adapted to be engaged by said member carrying the other end of the belt to release the gripping member from 35 the belt.

40 It is another object of the invention to provide said gripping units with belt engaging surfaces which are arranged eccentrically to the pivot of the units, whereby 45 said gripping member will be moved into belt clamping position due to the tension placed on the belt when in use.

45 It is a further object of the invention to provide a belt clamping member comprising a plurality of units which is pivotally mounted between the side flanges of a front plate, and a member carrying securing means for the other end of the belt also pivotally mounted between said flanges, said 50 clamping member and said last mentioned

member having independent pivotal movement relative to each other.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art, and as would fall within the scope of the claims.

In the drawings:

Fig. 1 is a plan view of a belt buckle embodying my improved belt clamping member taken from the rear side thereof showing a belt in position therein, the plate carrying one end of the belt being shown as being partly broken away;

Fig. 2 is a section taken on the line 2—2 of Fig. 1;

Fig. 3 is a transverse sectional view through the buckle taken at the pivot member for the clamping units; and

Fig. 4 is a side view showing one of the belt clamping units engaging one portion of the belt in full lines and another of the belt clamping units engaging said portion of the belt in dotted lines.

Referring in detail to the drawings, the improved belt buckle comprises a front plate 10 having rearwardly extending flanges 11 between which is mounted the pivot pin 12 which may be headed over as shown at 13 and upon which is pivotally mounted the plate 14 having the side flanges 15 between which is pivotally mounted at 16 the belt end gripping member 17 having the teeth 18 engaging with the belt end 19 and being provided with a handle portion 20 which is adapted to engage with the down struck stop member 21 provided on the plate 14. While one well known type of gripping member or ratchet is shown on this plate, it is to be understood that any form of fastening means can be used for securing the belt end 19 to the belt end carrying member 14 pivotally mounted between the side flanges 11 of the plate 10. Mounted on the pivot pin 12 is a plurality of similar belt gripping or clamping units 22, any number of which may be used, it being of importance that a sufficient number of these units is used so that the belt end 23 will be engaged by substantially all of said

units and the front plate 10, this being particularly of advantage where a front plate that is transversely as well as longitudinally curved, is used, such as the front plate 10, 5 which it will be seen is shown as being curved both longitudinally and transversely by reference to Figs. 2 and 3. Each of the belt clamping or gripping units 22 is provided with an opening 24 for receiving the 10 pivot pin 12, and is provided with a plurality of belt engaging members or teeth 25, the engaging surfaces of which are arranged eccentric to the opening 24 so that if the belt end 23 is moved to the left in Fig. 2, the 15 member 22 in assuming the position shown in full lines in Fig. 2 will be drawn into such a position that the harder the pull on the member 23 toward the left, the tighter the same will be clamped between the member 22 and the front plate 10, this being due 20 to the fact that the distance between the pivot 12 and the teeth 25 at the right of Figs. 2 and 4 is greater than the distance between the pivot pin 12 and the teeth 25 at the left 25 of said figures. Each of the members 22 is also provided with a substantially straight upper edge 26 which joins with the side edge 27 in a sharp corner 28. Each of said members 22 is also provided with a lug or projection 29 forming a sharp offset or shoulder at 30 and being provided with a curved outer surface at 31.

It will be noted from Figs. 1 and 2 that the lug 29 of each of the units 22 lies in 35 alignment with the rear edge portion 32 of the plate 14 so that when the plate 14 is swung in a counterclockwise direction in Fig. 2, the rear edge portion 32 will engage with the edge 30 on the lug 29 so as to swing 40 each of the units 22 in a counterclockwise direction, thus releasing the same from engagement with the belt end 23. It will also be seen that when the member 22 is out of belt 45 engaging position that if the member 14 is swung in a clockwise direction the undersurface thereof will engage with the edge 26 of each of the members 22 throwing them around in a clockwise direction, so as to move the same into belt engaging position. After 50 said members have been moved into belt engaging position a slight movement of the belt end 23 toward the left will cause said members to be moved into belt clamping position, said members assuming various angles relative to each other and relative to the front 55 plate 10 depending upon the distance between the pivot member 12 and the portion of the belt end 23 which the gripping or clamping units 22 engage. For example, the gripping 60 members or clamping members 22 adjacent the side edge portions of the belt end 23 will assume substantially the full line position shown in Fig. 4, whereby those nearer the center of the belt will assume substantially 65 the dotted line position shown in Fig. 4,

those between the side and middle portions of the belt assuming positions between the full and dotted line position shown in Fig. 4.

A belt gripping member of the character described above will grip the belt very 70 firmly, making it substantially impossible for the belt end 23 to slip relative to the front plate 10, and due to the fact that the gripping is done over substantially the entire 75 transverse portion of the belt in alignment with the gripping members, there will be no marring of the belt due to the gripping action of the members even when provided with teeth, such as shown. This is due to the fact that while the entire gripping member made up of the gripping units will engage the belt end 23 very firmly, it is only necessary for each unit to have a gentle 80 clamping action on the belt end to accomplish the desired purpose, this being principally due to the structure of the gripping member comprising a plurality of gripping units having independent pivoted movement relative to each other. It is to be understood 85 that the gripping member described above while being shown as being applied to one particular form of belt buckle may be used with other forms, and it will be obvious that the invention may be applied to numerous types of belt buckles, the important feature being that the gripping member is made up of a plurality of gripping units.

Having thus described my invention, what I desire to claim and secure by U. S. Letters Patent is:

1. In a belt buckle, a body portion, a clamping member mounted on said body portion for pivotal movement relative thereto, said clamping member comprising a plurality of adjoining clamping units having independent pivotal movement, and means for moving said clamping units into belt engaging positions.

2. In a belt buckle, a body portion, a clamping member mounted on said body portion for pivotal movement relative thereto, said clamping member comprising a plurality of adjoining clamping units having independent pivotal movement, and means for moving said units to belt releasing positions.

3. In a belt buckle, a body portion, a clamping member mounted on said body portion for pivotal movement relative thereto, said clamping member comprising a plurality of adjoining clamping units having independent pivotal movement, and a member for moving said units into belt engaging position, said member being provided with means for securing the other end of a belt thereto.

4. In a belt buckle, a body portion, a clamping member mounted on said body portion for pivotal movement relative thereto, said clamping member comprising a plu-

rality of adjoining clamping units having independent pivotal movement, and a member for moving said units to belt releasing position, said member being provided with means for securing the other end of a belt thereto.

5. In a belt buckle, a body portion and a clamping member pivotally mounted on said body portion, said clamping member comprising a plurality of narrow sheet metal belt engaging members arranged side by side in abutting relation and having independent pivotal movement, said belt engaging members engaging said belt edgewise of said members.

10 6. A belt buckle of the character described comprising a front plate and a belt end clamping element eccentrically pivotally mounted therein, said element comprising a plurality of adjoining individual belt engaging units, a member having means for securing the other end of a belt thereto pivotally mounted relative to said clamping element and means on said member engaging 15 said clamping element to move the same into clamping relation with said belt.

20 7. A belt buckle of the character described comprising a front plate and a belt end clamping element eccentrically pivotally mounted thereon, said element comprising a plurality of adjoining individual belt engaging units, a member having means for securing the other end of a belt thereto pivotally mounted relative to said clamping element, and means on said member engaging 25 means on each of said units to move the same out of clamping relation with said belt.

30 8. In a device of the character described, a belt buckle comprising a front plate, and a plurality of clamping elements for one end of said belt eccentrically pivotally mounted thereon, said clamping elements being mounted side by side in abutting relation for independent swinging movement relatively to each other and each having notched edge portions engaging said belt collectively providing a serrated belt engaging 35 surface.

40 9. In a device of the character described, a belt buckle comprising a front plate, a clamping element for one end of said belt and a clamping element for the other end of said belt, said elements being mounted for independent swinging movement about a common pivot pin in said front plate, and one of said elements being eccentrically mounted therein and comprising a plurality of independently pivoted clamping units arranged side by side in abutting relation.

45 10. In a device of the character described,

a belt buckle comprising a front plate, a clamping element for one end of said belt pivotally mounted therein and a gripping element for the other end of said belt pivotally mounted therein, one of said elements being eccentrically mounted therein, and the other of said elements being provided with means adapted to engage said first element to move said first clamping element into and out of clamping position, one of said elements comprising a plurality of independently pivotally mounted belt engaging units.

50 11. In a device of the character described, a belt buckle comprising a front plate, a member provided with means for securing one end of a belt thereto pivotally mounted on said front plate, and a clamping element for the other end of said belt pivotally mounted on said front plate, said element comprising adjoining belt engaging units 55 each having means thereon, whereby when said member is swung on its pivot away from said front plate, said member engages with said means to swing each of said units on its pivots to belt releasing position.

60 12. In a device of the character described, a belt buckle comprising a front plate, a member provided with means for securing one end of a belt thereto pivotally mounted on said front plate, and a clamping element for the other end of said belt pivotally mounted on said front plate, said element comprising belt engaging units having means thereon, whereby when said member is swung toward said front plate, said member 65 engages said means to swing each of said units independently toward belt engaging position.

65 13. In a belt buckle, a body portion and a clamping member mounted on said body portion for pivotal movement relative thereto, said clamping member comprising a multiplicity of closely spaced parallel sheet metal clamping units engaging edgewise with said belt.

70 14. In a belt buckle, a body portion, a belt gripping member mounted on said body portion for pivotal movement relative thereto, and an actuating member, said belt gripping member comprising a plurality of sheet metal gripping members arranged side by side with their flat faces adjoining and having a belt engaging portion along one edge thereof and means on the opposite edge thereof for engagement by the actuating 75 member.

75 In witness whereof, I hereunto subscribe my name this 9th day of March A. D., 1922.

SAMUEL BUCHSBAUM.
